(57) **CLAIM**

(21) Appl. No.: **29/346,306**

The ornamental design for a wooden hand carved two-doors swinging gate, as shown and described.

(22) Filed: **Oct. 29, 2009**

DESCRIPTION

(51) LOC (9) Cl. **25-02**

FIG. 1 is a perspective view of a wooden hand carved two-doors swinging gate showing my new design;

(52) U.S. Cl. **D25/50**

FIG. 2 is a front view thereof;

(58) Field of Classification Search D25/50;

256/73, 25, 26, 19; 49/50, 57

See application file for complete search history.

FIG. 3 is a back view thereof;

FIG. 4 is a side view thereof;

FIG. 5 is an opposite side view thereof;

FIG. 6 is a top view thereof; and,

FIG. 7 is a bottom view thereof;

In FIG. 1 and FIG. 2, the broken lines showing of environmental structure for purposes of illustrating the wooden hand carved two-doors swinging gate in a condition of use. The broken lines and the structure they depict form no part of the claimed design.
